UNITED STATES PATENT OFFICE

2,224,617

ROTARY DUST SEPARATOR IMPELLER

Stig G:son Sylvan, Stockholm, Sweden, assignor
to American Air Filter Company, Inc., Louis-
ville, Ky., a corporation of Delaware

Original application April 7, 1936, Serial No.
73,142. Divided and this application April 27,
1938, Serial No. 204,507

1 Claim. (Cl. 230—134)

This invention relates to improvements in im-
pellers for rotary dust separators of the char-
acter described in my copending application
Serial No. 73,142 of which this is a division.

5 The principal object of the invention is to
simplify the structural design and reduce the
manufacturing cost of impellers for rotary dust
separators.

The invention is illustrated in the accompany-
10 ing drawing, wherein:

Figure 1 is a front elevation of an impeller
constructed in accordance with my invention;

Figure 2 is a side view thereof with the lower
half in section and the upper half in elevation;
15 and

Figure 3 is a rear elevation.

The illustrated impeller, which is fixedly se-
cured to a rotatable drive shaft 2, includes a
20 conically shaped hub 3, an annular disc 4, a
series of blades 5 and a band 6. The hub 3 is
fixedly secured to the shaft 2 while the annular
disc 4 is similarly secured to the hub 3 and ar-
ranged to extend radially therefrom. The an-
25 nular outward pull exerted on the disc, as a
result of its rotation, increases from its periph-
ery inwardly to its points of securing to the
hub. Accordingly it is desirable to increase the
thickness of the disc from its periphery inwardly
30 in order to provide the requisite strength and at
the same time keep the weight of the disc at a
minimum. Heretofore the disc has been cast in
such form. In accordance with this invention
the same result is achieved in a simpler manner
35 and at less expense by riveting or otherwise se-
curing together a requisite number of plates of
different outside diameters. The number of
plates used will depend upon the strain to
be encountered and the thickness of each
40 plate. For the most part three to five plates of
suitable thickness have been found sufficient for
a wide range of impeller speeds and diameters
but a different number may of course be used as
the occasion may require. With three plates of
45 different diameter the strain in the outer section
of the disc is carried by the largest plate, in the
intermediate section thereof by the two larger
plates and in the inner section by all three. The
plate of largest diameter is preferably placed on

the air flow side of the disc as a whole in order
to provide a flat seating surface for the blades 5.

The blades 5 are fixedly secured to the disc and
arranged to project laterally therefrom across
the air flow. While the blades may be shaped
and arranged as desired, they are shown as of
flat shape and of straight radial arrangement.
The blades also should be inclined to the disc
in such manner as to cause particles precipitated
on them during rotation to move toward that 10
side of the air flow from which the particles are
to be removed. In the structure illustrated the
particles are to be removed from the disc side of
the air flow and consequently the blades are in-
clined forwardly across the air flow from the disc 15
4 to the band 6 so that the band edges of the
blades lead the disc edges thereof in the direc-
tion of rotation.

The band 6, which is secured to the adjacent
20 side edges of the blades, operates to stiffen the
blade structure as a whole. It has also been
found to improve the blower characteristics of
the device and for that reason is made wide
enough to cover the side edges of the blades
completely from their inlet to their outlet edges. 25
In this character of device, it is desirable that
the flow area at the outlet edges of the blades
be not greater and preferably smaller than the
area at the inlet edges thereof. For that rea-
son the band is made cone shaped and arranged 30
to approach the disc as it extends outwardly so
as to produce an outwardly converging cen-
trifuging passage, the slope of the band depend-
ing upon the inlet-outlet area ratio desired.

I claim:

An impeller of the class described comprising:
a hub having a securing flange; a unitary an-
nular disc fixedly mounted on said hub against
said flange, said disc being composed of a series
of at least three plates of different diameters 40
arranged in face-to-face relation and secured to
said flange and to each other, the diameters of
said plates progressively decreasing in one direc-
tion from the largest plate of the series to the
smallest plate thereof; and a series of fluid- 45
propelling blades fixedly secured to said disc.

STIG G:SON SYLVAN.
